UNITED STATES PATENT OFFICE.

MAURICE G. KLEMME, OF BELLEVILLE, ILLINOIS.

GAS-STOVE BURNER.

Application filed September 10, 1924. Serial No. 736,933.

The invention relates to gas stove burners and has for its object to provide a device of this character adapted to be disposed within a gas stove beneath the bottom of the oven and provided with right angularly disposed branches adapted to register with the flues at opposite ends of the oven and form means whereby the oven will be quickly and uniformly heated with an even heat inside and out, thereby insuring the best results during a baking operation, and at the same time allowing the heating of the oven in a minimum amount of time.

A further object is to provide the intake pipe centrally of the burner thereby insuring a distribution of the gas evenly throughout the burner and giving an even amount of fuel over the entire burning surface.

A further object is to extend the gas supply pipe of the burner through the rear of the stove, thereby eliminating unsightly pipes at the forward side of the stove.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a top plan view of the burner.

Figure 2 is a vertical longitudinal sectional view through lower portion of a conventional form of gas stove showing the burner disposed therein.

Figure 3 is a vertical transverse sectional view through the lower portion of a conventional form of gas stove showing the burner therein.

Referring to the drawing, the numeral 1 designates a conventional form of gas stove, 2 the end walls thereof and 3 the oven. Disposed beneath the bottom 4 of the oven is a burner 5. Burner 5 comprises a longitudinally disposed horizontal section 6, from the opposite apertures 7 of which gas is discharged and burnt in a manner whereby the flames will contact with the bottom 4 of the oven and quickly heat the same. The ends of the burner section 6 terminate in transversely disposed pipe members 8 which have their upper sides provided with

gas discharging apertures 9, and from which apertures gas is discharged and consumed in a manner whereby flames will extend upwardly into the flues 10 at opposite ends of the oven 3, consequently the oven is uniformly heated thereby insuring even baking, and the heating of the oven in a minimum amount of time.

Gas is supplied to the burner substantially centrally thereof, through the pipe 11, consequently a uniform flow of gas will be furnished at all points of the burner, and in both transversely disposed pipes 8, consequently a more uniform heat radiation is obtained. The pipe 11 preferably extends through the rear wall 12 of the stove thereby obviating any piping at the forward side of the stove which materially detracts from the appearance of the stove. The burner on its under side is provided with supporting legs 12, which support the same spaced from the bottom of the stove and adjacent the bottom 4 of the oven.

From the above it will be seen that a gas stove burner is provided which is disposed beneath the oven of the gas stove and provided with transversely disposed burner pipes in registration with the end flues at opposite ends of the oven, thereby insuring a uniform and quick heating of the oven and maximum baking efficiency of the oven.

The invention having been set forth what is claimed as new and useful is:—

The combination with a gas stove having an oven therein and vertically and transversely disposed flues at opposite ends of said oven, of a burner disposed beneath said oven and comprising a longitudinally and horizontally disposed burner pipe beneath the oven substantially beneath the longitudinal center of the oven, said burner pipe having its ends terminating adjacent the lower ends of the vertically and transversely disposed flues, transversely disposed burner pipes carried by the ends of the first mentioned burner pipe in registration with the lower ends of said flues and extending substantially the full length thereof and a gas supply pipe connected to said first mentioned burner pipe substantially centrally thereof beneath the oven.

In testimony whereof I have signed my name to this specification.

MAURICE G. KLEMME.
